UNITED STATES PATENT OFFICE.

JOHN K. RISHEL, OF WILLIAMSPORT, PENNSYLVANIA.

TABLE-LOCK.

SPECIFICATION forming part of Letters Patent No. 759,812, dated May 10, 1904.

Application filed April 20, 1903. Serial No. 153,553. (No model.)

To all whom it may concern:

Be it known that I, JOHN K. RISHEL, a citizen of the United States, residing at Williamsport, in the county of Lycoming and State of Pennsylvania, have invented a new and useful 5 Table-Lock, of which the following is a specification.

This invention relates to table-locks, and is particularly designed for use in securely locking together the parts of a pedestal extension-table to counteract any tendency of the pedestal parts to sag or spread apart.

Another object of the invention is to provide means within convenient reach which can be 15 expeditiously and effectually operated to connect or release the separate pedestal parts.

Further objects and advantages of this invention will appear in the following description, and the novel features thereof will be particularly pointed out in the appended claims, 20 it being understood that various changes in the form, proportion, and the minor details of construction may be resorted to without departing from the spirit or sacrificing any of the advantages of this invention.

In the drawings, Figure 1 is a side elevation of an extension-table containing my invention, the table-top and pedestal being broken away and shown in vertical section, disclosing the 30 interior parts of the mechanism. Fig. 2 is a detail side elevation of the lock applied to the interior of the pedestal, presenting the operating parts of the locking mechanism prior to their engagement; and Fig. 3 is a detail top plan view of the operating-lever.

The reference-numerals 1 and 2 designate two table-top sections carried by the hollow pedestal-sections 3 and 4, which are supported upon the spread feet 5 and 6. The pedestal 40 formed by the two complementary members 3 and 4 is of the box form, so as to encompass the center leg 7, the lower end of which projects therethrough, so as to rest upon the floor.

When the pedestal parts are brought together, as shown in Fig. 1, any pressure upon the table-top will be transmitted upon the spread feet, and the tendency will be to spread, so as to cause an unsightly crevice or seam to occur, as well as weaken the table throughout.

50 In order to overcome or counteract the tend-

ency of the parts to spread, I provide a locking device which consists of a lever-operated pivoted catch carried by one of the pedestal-sections and engaging a complementary part on the opposing pedestal-section.

55

The catch is designated by the reference-numeral 8 and is illustrated as being pivotally mounted to a bearing-plate 9, secured to one of the pedestal-sections and in line with the complementary part 10, comprising a pin carried by the opposing pedestal part and which is adapted to be engaged by the hook-shaped terminal 11, forming a part of the catch 8. In order to prevent a displacement of the catch, as well as to limit its movement, I provide a guide-loop 12 on the plate 9, through which the catch projects.

60

An operating mechanism is provided for the catch, which consists of a vertically-disposed and pivoted lever 13, movable on its fulcrum 70 14 by a horizontal handled lever 15, connected to the lever 13 by a link 16. The curved toe 17 of the lever 13 engages the projection 18 on the catch 8 to release the catch from engagement with part 10; but if it is desired to cause 75 the pedestal parts to become locked a movement of the handle 15 will cause the lever 13 to engage the top edge of the catch, and thereby force it into engagement with the part 10, where it will be retained until the handle-lever 15 is reversed to cause the toe 17 of the lever 13 to engage the projection 18 to release it.

80

In actual practice the catch 8 will be terminally pivoted at the end opposite to that at 85 which the hook 11 is carried, and the projection 18 is inclined at an acute angle to the longitudinal edges of the catch, so as to provide means whereby a quick-positive action can be imparted to the catch, whether the pedestal 90 parts are being released or connected. The handle-lever 15 will preferably be located beneath one of the table top sections so as to be within easy reach of the operator, and as the point of connection of the link with the lever 15 is at an eccentric to the point of connection of the lever with the table said lever will be held in either position to which it is adjusted.

95

Having thus described the invention, what I claim is—

100

1. In a pedestal extension-table the combination with a vertically-divided pedestal and the two separable parts of the table-top carried by the pedestal parts, of means for securing the pedestal parts together, comprising a latch-bar on one of the pedestal parts for engagement with a complementary device on the other pedestal part, terminally pivoted to the pedestal part and having an inclined projection at one end, and a lever carried by the said pedestal part having a toe for contact with the inclined projection to release the latch-bar, and movable to bear upon a point intermediate the ends of the latch-bar to hold it in engagement with the complementary device.
2. In a pedestal extension-table, the combination with a vertically-divided pedestal and the two separable parts of the table-top carried by the pedestal parts, of means for se-

curing the pedestal parts together, comprising a pivoted catch on one of the pedestal parts for engagement with a complementary member on the adjacent pedestal part, a forwardly-disposed projection on the catch, and a lever pivoted to the pedestal part on which the catch is secured, said lever having a toe for engagement with the projection to release the catch and movable to a point intermediate the ends of the catch so as to bear thereon and hold the catch in a locked position.

In testimony that I claim the foregoing as my own I have hereto affixed my signature in the presence of two witnesses.

JOHN K. RISHEL.
